UNITED STATES PATENT OFFICE

AUGUST ENSTROM, OF CHICAGO, ILLINOIS, ASSIGNOR TO PETTIBONE MULLIKEN COMPANY, OF CHICAGO, ILLINOIS, A CORPORATION OF DELAWARE

SWITCH POINT-RAIL

Application filed October 23, 1930. Serial No. 490,751.

My invention relates more particularly to switch point-rails of the type comprising a point-rail proper recessed at its pointed extremity and a separate wear-resisting point-section removably secured in said recess.

In present railway construction the point-rails of switches are subjected to great wear at the pointed extremities thereof, the remainder of the point-rail remaining in good condition.

It is thus desirable to provide a point rail of such construction that when such wear of its pointed extremity occurs as to render it unfit for further use, the rail may be reconditioned for service and thereby avoid the scrapping of the rail which, as above stated, remains as to its greater part in good serviceable condition.

One of my objects is to provide a construction of point rail of the type above referred to, whereby its removable point section may be readily and quickly applied to and removed from operative position on the point-rail proper and another point section substituted therefor at will and without removing the point rail from the track.

Another object is to provide an economical construction of point-rail of the type referred to which shall not require any welding operation, and the point portion of which will withstand the jarring action to which it is subjected in use from either side of the rail without shifting on the point-rail proper.

Another object is to provide a point-rail of such construction that the lateral forces to which the pointed extremity of the rail is subjected in use will be resisted in such a way as to lessen shock to such pointed extremity.

Another object is to minimize danger of cracking of the point rail proper at its recessed portion; and other objects as will be manifest from the following description.

Referring to the accompanying drawings:

Figure 1 is a plan view of the pointed end portion of a point-rail embodying one form of my invention, this rail being shown in switching position relative to a main rail shown by dotted lines.

Figure 2 is a plan sectional view of the point-rail, the adjacent main rail being shown by dotted lines.

Figure 3 is a view in side elevation of the structure shown in Figs. 1 and 2.

Figure 4 is an end view of the point rail, the point rail being viewed from the left hand side of Fig. 3 and the adjacent main rail being shown by dotted lines.

Figure 5 is a section taken at the line 5—5 on Fig. 3 and viewed in the direction of the arrows, the adjacent main rail being shown by dotted lines.

Figure 6 is a section taken at the line 6—6 on Fig. 3 and viewed in the direction of the arrows.

Figure 7 is a view in longitudinal sectional elevation of the point-rail, the section being taken at the line 7—7 on Fig. 4 and viewed in the direction of the arrows.

Figure 8 is a perspective view of the separable point-section of the construction of the preceding figures.

Figure 9 is a broken fragmentary perspective view of the pointed extremity of the point-rail proper.

Figure 10 is a view like Fig. 2 of another embodiment of the invention.

Figure 11 is a view in side elevation of still another embodiment of the invention, the adjacent main rail being shown by dotted lines.

Figure 12 is a plan sectional view of the structure of Fig. 11; and

Figure 13, a section taken at the line 13—13 on Fig. 11, the adjacent main rail being shown by dotted lines.

Referring to Figs. 1 to 9 inclusive, the structure therein shown comprises a point-rail 14 represented in switching position relative to an adjacent main rail 15.

The point-rail 14, which is tapered toward one end in accordance with common practice, is formed of a point-rail proper 16 recessed along the upper surface of its pointed extremity as represented at 17, this recess extending downwardly into the web 18 of the point-rail proper and its end wall being preferably curved as represented at 19.

The point-rail also comprises a point-forming section 20 separate from the point-rail proper 16 and preferably constructed of metal highly resistant to the forces to which the point portions of point rails are subjected. By way of example the point-section 20 in use, may be a steel forging heat treated to harden it.

The point-forming section 20 is removably secured in the recess 17 whereby when the point section 20 has become unduly worn it may be removed from the point-rail proper and another substituted for it.

In the construction now being described the point-forming section 20 is formed of a body portion 21 the upper head portion 22 of which is tapered toward its outer end as shown and in accordance with common practice.

The body portion 21 of the section 20 is grooved along its under side as represented at 23 to provide spaced apart substantially parallel flange portions 24 which depend from the head portion 22. The point-section 20 when applied to operative position on the point-rail proper extends at its head portion 22 into the recess 17 and at its flange portions 24 straddles the web 18 of the point rail proper, it being preferred that the groove 23 be of such width as to require the forcing of the point section 20 to seated position on the point-rail proper, thus causing the flanges 24 to be slightly outwardly sprung.

The body-portion 21 is provided at its rear end with a bar 25 forming a continuation of one of the flanges 24, the bar 25, in the assembling of the point section 20 with the point-rail proper, extending into the space at one side of the point-rail proper defined by the head, web and flange of the point-rail proper as shown particularly in Fig. 6.

In the construction now being described means are provided for reinforcing the point-section 20 against lateral displacement, these means comprising a metal bar 26 which extends into the space at the side of the point-rail proper opposite that into which the bar 25 extends and defined by the head, web and flange of the point-rail proper. The outer end of the bar 26 is deflected outwardly as represented at 27 at which portion it overlaps the adjacent end of one of the flanges 24 the surface thus overlapped being chamfered as represented at 28 to permit thelapping end of the bar 26 to conformingly fit against this flange.

The point section 20 is preferably fastened to the point-rail proper 16 by any suitable means, such as the bolts represented at 29 which extend through openings in the flanges 24, bar portion 25 and web 18, certain of these bolts also extending through the reinforcing bar 26 and others thereof being shown as securing to the point-rail a clip 100 for connection with a bar (not shown) commonly provided for connecting together adjacent switch-point rails.

The joint between the point-rail proper 16 and the point-forming section 20, is preferably inclined as represented at 101 to reinforce the structure against lateral displacement of the point-forming section 20 relative to the point-rail proper 16 in the exertion of forces against it in one direction by the wheels running over the switch. It will be understood, however, that if desired this joint may be at a right angle to the side of the point-rail proper 16.

The construction shown in Fig. 10 is the same as that shown in the preceding figures except that the bar 26 instead oflapping the adjacent end of the point-section 20 extends in end-wise abutting relationship thereto as shown.

In the construction shown in Figs. 11, 12 and 13 the point-rail proper represented at 30 and recessed at 31 at its outer extremity as explained with respect to point-rail 16, is provided with a point-section represented at 32 which extends into the recess 31. The point-section 32 has a bar-extension 34 at one end and as explained with respect to point section 20, and depending spaced flanges 35 like the flanges 24 except that one of these flanges is comparatively shallow as shown at 36 and instead oflapping directly over the web 33 of the point-rail proper laps the upper edge portion of one end of a reinforcing bar 37 lying flatwise against the web 33 and thence extending rearwardly of the body portion of the point section 32, this rearwardly extending portion being represented at 38 and corresponding with the straight portion of the bar 26.

Fastening means, such as bolts 39, secure together the various flatwise-opposed portions of the point-rail structure, it being noted that those of the bolts which extend through the flanges 35 also extend through the forward end of the bar 37 which is recessed at 40 to receive the adjacent shallow flange 35 of the point section 32.

It will be understood that while the joints between the point-rails proper and the point-forming sections of the structures shown in Figs. 10 to 13, inclusive, extend at right angles to the sides of the point-rails proper, they may be so formed, if desired, that they will incline relative to the point-rails proper as shown in the construction represented in Figs. 1 to 9, inclusive.

While I have illustrated and described certain forms of structure embodying my invention, I do not wish to be understood as intending to limit it thereto as the invention may be embodied in other forms of structure and those illustrated variously modified and altered without departing from the spirit of my invention.

What I claim as new, and desire to secure by Letters Patent, is:

1. A point-rail comprising a point-rail proper containing a recess in the upper portion of its pointed end, and a separate point-section comprising a body portion located in said recess and having depending flanges integral therewith by means of which said point-section straddles said point-rail proper, the joint between the end wall of said recess and the adjacent end of said point-section being inclined relative to the sides of said point-rail proper.

2. A point-rail comprising a point-rail proper containing a recess in the upper portion of its pointed end, a separate point-section comprising a body portion located in said recess and having depending flanges integral therewith by means of which said front section straddles said point-rail proper, and fastenings securing said point-section on said point-rail proper, said recess and the adjacent end of said point-section being inclined relative to the sides of said point-rail proper.

3. A point-rail comprising a point-rail proper containing a recess in the upper portion of its pointed end, a separate point-section comprising a body portion located in said recess and having depending flanges by means of which said front section straddles said point-rail proper, and a reinforcing bar portion at the rear end of said point-section and extending flatwise against said point-rail proper.

4. A point-rail comprising a point-rail proper containing a recess in the upper portion of its pointed end, a separate point-section comprising a body portion located in said recess and having depending flanges by means of which said front section straddles said point-rail proper, and a reinforcing bar portion at the rear end of said point-section and integral with the body portion of said point-section and extending flatwise against said point-rail proper.

5. A point-rail comprising a point-rail proper containing a recess in the upper portion of its pointed end, a separate point-section comprising a body portion located in said recess and having depending flanges integral therewith by means of which said point-section straddles said point-rail proper, and a reinforcing bar portion at the rear end of said point-section and integral with said body portion and flanges and extending flatwise against said point-rail proper.

6. A point-rail comprising a point-rail proper containing a recess in the upper portion of its pointed end, a separate point-section comprising a body portion located in said recess and having depending flanges at 70 which said point-section straddles said point-rail proper, said flanges extending substantially throughout the entire length of said recess, and a reinforcing bar portion at the rear end of said point-section and flatwise 75 opposing said point-rail proper.

7. A point-rail comprising a point-rail proper containing a recess in the upper portion of its pointed end, a separate point-section comprising a body portion located in 80 said recess and having depending flanges by means of which said point-section straddles said point-rail proper, and a reinforcing bar secured to said point-rail proper and cooperating at one end thereof with the adjacent 85 end of one of said flanges, for the purpose set forth.

8. A point-rail comprising a point-rail proper containing a recess in the upper portion of its pointed end, a separate point-section comprising a body portion located in 90 said recess and having depending flanges by means of which said point-section straddles said point-rail proper, and a reinforcing bar secured to said point-rail proper and overlapping at one end the adjacent end of the 95 adjacent one of said flanges.

9. A point-rail comprising a point-rail proper containing a recess in the upper portion of its pointed end, a separate point-section comprising a body portion located in 100 said recess and having depending flanges by means of which said point-section straddles said point-rail proper, and a reinforcing bar secured to said point-rail proper and endwise 105 abutting the adjacent one of said flanges.

10. A point-rail comprising a point-rail proper containing a recess in the upper portion of its pointed end, a separate point-section comprising a body portion located in 110 said recess and having depending flanges by means of which said point-section straddles said point-rail proper, and a reinforcing bar secured to said point-rail proper and extending into the space between said flanges. 115

11. A point-rail comprising a point-rail proper containing a recess in the upper portion of its pointed end, a separate point-section comprising a body portion located in 120 said recess and having depending flanges by means of which said point-section straddles said point-rail proper, and a reinforcing bar secured to said point-rail proper and extending into the space between said flanges, said reinforcing bar containing a recess into 125 which the adjacent one of said flanges extends.

12. A point-rail comprising a point-rail proper containing a recess in the upper portion of its pointed end, and a separate point- 130

section comprising a body portion located in said recess and having depending flanges by means of which said point section straddles said point-rail proper, the distance between said flanges being such that in the applying of said point-section to straddling position on said point-rail proper said flanges are sprung slightly outwardly.

AUGUST ENSTROM.
